O. STRUFE

REFRIGERATOR AND INSTALLATION CONSTRUCTION THEREFOR

Filed June 4, 1927

Patented Sept. 25, 1928.

1,685,248

UNITED STATES PATENT OFFICE.

OTTO STRUFE, OF DWIGHT, ILLINOIS.

REFRIGERATOR AND INSTALLATION CONSTRUCTION THEREFOR.

Application filed June 4, 1927. Serial No 196,498.

This invention relates to refrigerators of the kind illustrated, described and claimed in Letters Patent granted to me on February 15, 1927 as No. 1,617,552, entitled Refrigerator.

5 The object is to provide additional parts or construction features enabling the refrigerator to be installed advantageously, cheaply and easily for use.

My said patent shows a refrigerator having 10 an extension of the ice receptacle part adapted to pass deeply into or through a hole in the building wall, with the door at the outer end of the extension, thus providing peculiarly advantageous means for what is known as 15 outside icing, together with other benefits and advantages as in the patent set forth or readily to be appreciated by those skilled in the art.

The problems which confronted me in connection with the matter of installation were 20 such as how to accomplish this by means which could be satisfactorily applied by the ordinary workman, by means which would be of such small additional cost as not to be 25 prohibitive or objectionable in any instance, by means which would provide the desired features of protection for the refrigerator, and by means affording a proper finish to the completed job. There were involved also 30 such considerations as the desirability of avoiding a special construction of the refrigerator, as to the length of its extension, for various installations, and that the refrigerator should be readily available for application to houses already built as well as to 35 houses under construction.

In the accompanying drawings forming a part hereof, Figure 1 is a fragmentary vertical section through a refrigerator such as is 40 illustrated in my said patent and with construction features of the present invention applied thereto and to the building wall; Fig. 2 is an outer or front view of the construction of Fig. 1; Fig. 3 is a vertical section as on the line 3—3 of Fig. 1; Fig. 4 is a perspective of a 45 sheet-metal tubular or sleeve-like member shown in Figs. 1 and 3; and Fig. 5 is a fragmentary section like that of Fig. 1 showing a modification in the sheet-metal covering and extension feature.

Referring to all of the figures the refrigerator 50 has a rear wall 12, a top wall 13, a top extension wall 13^a, a bottom extension wall 14, and side extension walls 15 (Fig. 3), and a door 16 closing the outer end of the extension.

If the extension as 15 be made of some

standard length in its fore-and-aft directions, as should ordinarily be done out of cost considerations, thus avoiding special constructions for particular jobs, the extension will 60 necessarily have different relations to the outside surface of different building walls as 18 which walls vary in thickness. The presence or absence of such an element as the base-board 19, Fig. 1, holding the rear wall 12 away 65 from the inner wall of the building, is a factor in the variations encountered. Where a wall is unusually thin it may be desirable to provide such a spacer as 19 of appropriate thickness. 70

In order to install a refrigerator having such an extension as 15 it is first necessary in old buildings to cut an appropriate hole for it through the building wall. The ordinary workman would not cut such a hole with any 75 measure of exactness, but even if the hole were a fairly exact one these improvements would still be required for the most satisfactory results. The hole 20, Fig. 1, is shown as being somewhat irregularly cut and as being substantially larger than the extension 15. 80

Rats frequently gnaw into, and their dead bodies have been found within, refrigerator walls. Since the building walls, particularly in frame buildings, are full of open spaces, 85 as between the studding, rats and other vermin in the walls would have free and convenient access to the extension part as 15. One feature of the present invention relates to protection against vermin. 90

Referring to Figs. 1 and 3, in this preferred construction, I first cover the extension walls with sheet metal such as tin or galvanized iron, and this is preferably done by nailing upon the wall 13^a the metallic plate 95 21, on the bottom wall 14 of the extension the metallic plate 22, and on the side walls 15 of the extension respectively the metallic plates 23, these plates being in all instances coextensive with the surfaces respectively to which they are applied. No forming of the metal plates is required. This covering, which may be applied by the manufacturer or by the person making the installation, protects the extension from vermin, including wood-boring insects, and also against moisture. 100 105

The auxiliary covering and extension device, indicated as a whole by the reference character 25 (Fig. 4) may be provided in 110 probably its simplest and cheapest form as two substantially U-shaped pieces of thin

sheet metal, preferably copper or galvanized iron, marked A and B. The part A has a horizontal reach 26 and two ends 27 bent therefrom at right angles, while the part B 5 has a horizontal reach 28 and similar ends 29, the ends 27 and 29 overlapping each other. This extension member 25 will ordinarily not be attached by the manufacturer, but it may be supplied by him as an article of manufacture, or the person installing the refrigerator 10 may readily bend these members into shape from easily obtainable stock.

When the refrigerator is to be installed the hole 20 in the building wall having been 15 produced, the workman ascertains the distance on the line x—y of Fig. 1, which distance includes first such spacing from the inner wall as may be caused for example by the baseboard 19, and secondly the thickness 20 of the outer facing element or frame denominated as a whole by F. Knowing this distance, and while the refrigerator is entirely away from the building wall, the sheet metal member B of Fig. 4 is applied at such a place 25 on the refrigerator extension 15 as to bring its outer edge preferably flush with the outer surface of the frame F. Nails 30 passing through the top reach 28 will hold this member or part B in its proper position. The 30 bottom member A is then applied as shown in Fig. 4 with its end members 27 overlapping and overlying the end members 29 respectively. Such overlap protects against weather 35 at the exposed portions. Nails 31 passing through the overlapped portions hold them securely together and also upon the refrigerator extension. The nails may be multiplied as deemed suitable.

The refrigerator is then moved so that the 40 extension 15 and its metallic extension and covering parts project into and through the building wall as shown in Fig. 1. The fact that the opening 20 is considerably larger than the extension facilitates the installation.

45 The next step is to apply a border-like member shown as the frame F which, as shown in Fig. 2, consists of an upper reach 33, a lower reach 34, and side reaches 35. Fig. 1 shows that this frame F is applied so as to fit tightly 50 around the extension provided by the rectangular sheet metal tubular or sleeve-like member 25 of Fig. 4. The frame F may be held upon the building wall by nails or otherwise according to the building construction 55 or preference, and nails 36, Fig. 1, as many as may be desired, hold the outer edge portions of the sheet-metal extension 25 tightly and in substantially weather-proof relation to the frame F. A coating of wet paint on 60 the inside edge of the frame F just before it is applied would produce a practically weather-proof joint at this place. The frame F thus affords a good finish and closes the outer margins of the hole 20 and it cooperates 65 in making a tight and strong construction.

Where there is such a spacing element as the baseboard 19 it will be advantageous to apply strips of corresponding thickness, as 70 37, Fig. 1, to the rear wall 12 of the refrigerator to close the inner bottom margin of the opening as 20 through the building wall. Other strips such as 38 and 39 may be applied to the inner surface of the building wall to close the inner margins of the opening 20 around the refrigerator at the top and sides. 75

While ordinarily not necessary, an additional feature of advantage is shown in weather strips 40, Figs. 1 and 2, in the form of quarter-round pieces applied in the corners at the outer extremity of the refrigerator 80 extension 15. These strips are an additional protection against weather and add finish.

In Fig. 5 parts already described are given the same reference characters respectively. In this modification the covering plates 21, 85 22 and 23 are omitted and the covering and extension device of Fig. 4 is made in the first instance unnecessarily long so as to provide an excess to be cut away as a final operation. These parts are marked A—A and B—B in 90 Fig. 5 and constitute at once the complete covering for the refrigerator extension 15 and that extension part of the covering adapted to be secured to the outer frame F. According to this construction the workman who installs the job simply nails the parts A—A and B—B upon the refrigerator extension body and then moves the refrigerator into place and applies the outer frame F, nailing the parts A—A and B—B to the frame F. 95 These parts A—A and B—B are long enough to take care of all variations in the thickness of the building wall ordinarily encountered, and therefore in most instances there will be a part thereof, shown by dotted lines in Fig. 5, 100 extending outwardly beyond the frame F. As a final operation this excess is cut away. This may be done by the ordinary workman by means of a hack saw, beginning at one corner, cutting in with snips from the free edges, 105 removing the excess material at that corner, and then proceeding with the hack saw all the way around. He could also use a sharp chisel as the metal is thin and the frame F would furnish ample support. 110

According to these constructions the installation of the refrigerator may be effected in a very simple and easy way, with the result of a strong and weather-proof construction, 115 of neat appearance, and with the refrigerator thoroughly protected from the dangers mentioned. The effect is further to hold the refrigerator strongly in its established position so that it may not be pushed inward, as might under some circumstances be done by a person seeking to gain unauthorized entrance into the building.

I contemplate as being included in these improvements all such changes, variations and departures from what is thus specifically 120 125 130

illustrated and described as fall within the scope of the appended claims.

I claim:

1. The combination with a refrigerator having a body extension of the character described adapted to pass deeply into an opening through a building wall, of a metallic covering surrounding the extension and projecting to the outside of the building wall.
- 10 when the refrigerator is normally installed, with a border-like member at the outer extremity of said covering for closing the outer margins of the opening through the building wall.
- 15 2. The combination with a refrigerator having a body extension of the character described adapted to pass deeply into an opening through a building wall, of a pair of substantially U-shaped sheet metal members sur-
- 20 rounding the extension and projecting to the outside of the building wall when the refrigerator is normally installed, with means associated with said U-shaped members for clos-
- 25 ing the outer margins of the opening through the building wall.
3. The combination with a refrigerator having a body extension of the character described adapted to pass deeply into an opening through a building wall, of a sleeve-like
- 30 member surrounding the extension and tele-
- 35 scopically adjustable so as to extend to a pre-determined place adjacent to the outside of the building wall when the refrigerator is normally installed, with means associated with said sleeve-like member for closing the outer margins of the opening through the building wall.
4. The combination with a refrigerator having a body extension of the character de-
- 40 scribed adapted to pass deeply into an open-

ing through a building wall, of a metallic sleeve-like member telescopically adjustable on the extension to extend to a predetermined place adjacent to the outside of the building wall when the refrigerator is normally installed, and a frame secured to the building wall and surrounding the outer edge portions of the sleeve-like member, said outer edge portions being secured to the frame.

5. The combination with a refrigerator having a body extension thereof projecting deeply into an opening through a building wall, of a protective cover surrounding and substantially coextensive with said extension, a protective sleeve overlying said cover and extending to the outside of the building wall when the refrigerator is normally installed, and means at the outer end of the sleeve closing the outer margins of the opening through the building wall, said sleeve being permanently held upon said cover and at its outer end in permanent relation to the building wall.

6. The combination with a refrigerator having a rectangular body extension projecting into an opening through a building wall, of a metallic plate covering the upper, lower and side surfaces respectively of said extension, a metallic sleeve surrounding said so-covered extension and extending to the outside of the building wall when the refrigerator is normally installed, said sleeve and said plates being permanently secured to the refrigerator extension, and a frame at the outer end of the sleeve closing the outer margins of the opening through the building wall, said sleeve being permanently secured to said frame.

OTTO STRUFE.
